[57] CLAIM

The ornamental design for a dashboard cover, as shown and described.

DESCRIPTION

FIG. 1 is a perspective view of a dashboard cover showing my new design in exploded condition with respect to the dashboard, it being understood that the broken lines are for illustrative purposes only;

FIG. 2 is an enlarged top plan view thereof;

FIG. 3 is an enlarged bottom plan view thereof; and

FIG. 4 is an enlarged end elevational view thereof.
